UNITED STATES PATENT OFFICE.

ABRAHAM S. BECKER, OF BALTIMORE, MARYLAND.

DESIGN FOR A CORSET.

59,537.

Specification for Design.

Patented Nov. 1, 1921.

Application filed June 2, 1920. Serial No. 386,070. Term of patent $3\frac{1}{2}$ years.

To all whom it may concern:

Be it known that I, ABRAHAM S. BECKER, a citizen of the United States, residing at Baltimore, in the State of Maryland, have invented a new, original, and ornamental Design for a Corset, of which the following is a specification, reference being had to the accompanying drawing, forming part thereof.

The figure is a perspective view of a corset, showing my new design.

I claim:

The ornamental design for a corset, as shown.

ABRAHAM S. BECKER.
